STAPLING DEVICE

William D. Faltz, Pittsburgh, Pa.

Application May 17, 1940, Serial No. 335,753

7 Claims. (Cl. 1—49)

My invention relates to a hand operable stapling device that can be held and manipulated in one hand.

One object of my invention is to provide a simple hand operable stapler that can be constructed with sufficient simplicity of design to permit it to be made in small dimensions to be incorporated in the top portion of the shell of a conventional mechanical pocket pencil.

Another object of my invention is to provide a hand operable stapler that shall be sufficiently small in size and light enough in weight to permit it to be held in one hand while at the same time having its design so arranged that the staple pressing member may be operated by the thumb.

Another object of my invention is to provide a hand stapler as part of a conventional pocket pencil; with the shell of the device formed in two tubular portions to permit access to a magazine in one tubular portion for refilling purposes; and for placement of a pusher slide beyond the staples; with a biasing spring properly supported within the other portion of the shell to rest against and press the pusher slide forward; both portions of the shell being suitably locked and fastened against the reaction force of the biasing spring.

The combination stapler and pencil that is constructed in accordance with the principles of my invention is illustrated in the accompanying drawings, in which

Figure 1 is a longitudinal vertical sectional view, through the stapler and pencil, showing the stapler mechanism in one part of the shell and the pencil element in the other part of the shell, with the biasing spring that pushes the staples into position shown disposed between the two parts of the shell;

Figure 2 is a view similar to that shown in Figure 1, except that the supporting rod for the biasing spring and for the stapler pusher is formed eccentrically with respect to the central axis of the device to permit the mechanism to be enclosed within a shell of smaller diameter than in the construction shown in Figure 1;

Figure 3 is a sectional view of part of the structure enlarged to show the arrangement between the staple driver and the anvil plate;

Figure 4 is a transverse view partially in section, and partially in elevation, to show the disposition of the staple driver, and a staple, when the staple is completely closed on the papers;

Figure 5 is an elevational view of the staple driver;

Figure 6 is a transverse section along lines 6—6 in Figure 2;

Figure 7 is an enlarged view of the portion of the barrel, in which the pivoted end of the guide rod is supported;

Figure 8 is a view of a modification whereby the end of the guide rod is supported by a disc, instead of by a hole in the barrel;

Figures 9 and 10 are respectively a plan end

10 and elevational views of the stapler of Figure 2;

Figure 11 is a plan view of the stapler in Figure 2 showing the manner in which the anvil plate is seated in a recess in the barrel body, as partly shown in Figure 6;

15 Figure 12 is a longitudinal section, partially in elevation, of a portion of the stapler adjacent the pressure bar to illustrate the mounting of a lifting lever.

Figure 13 is a plan view showing the disposition

20 of the lifting lever;

Figure 14 is a perspective view of a metallic assembly providing the magazine and the fitted passages for the staples;

Figure 15 is a perspective view of the forward

25 wall channel for the fitted passage;

Figure 16 is a sectional view through a portion of the stapler formed upon the metallic structure of Figure 14;

Figure 17 is a view similar to Figure 16, show-

30 ing the disposition of the staples and the anchor-

ing plate, and stock pin for the staple driver;

Figure 18 is a view similar to Fig. 6, showing

the metal guide member as molded in the maga-

35 zine body of the stapler; and

Figure 19 is a side elevation with part broken

away of a unit as in Fig. 1 with the parts of Fig.

14 molded in the body.

As shown in the drawings, the combination

40 stapler and pencil 10 comprises a top tubular shell 11 and a bottom tubular shell 12, that are

arranged to be mechanically joined by threads

13 or other equivalent means. The shells are

preferably made of molded plastic materials.

One shell, preferably the top one 11, is threaded

45 internally at the inner or lower end, and the

other shell 12, is threaded externally at the inner

or top end. The top shell 11 serves as a maga-

50 zine and is provided with an internal longitudinal

magazine passage 14 to receive and guide a unit

55 batch of staples 15. The magazine passage 14

extends almost the full length of the top shell

11, to the front end of the shell where the longi-

tudinal magazine passage 14 communicates with

a transverse pressure or feed slot or passage 16,

for a plunger or staple driver 17. The staple

driver or plunger 17 separates the leading staple from the batch and forces it through the papers to be stapled.

A spring-biased feeder or pusher 18 is adapted to be disposed behind the batch of staples, to force them forward in the magazine passage 14, to move the leading staple of the batch to the transverse feed slot 16, where that leading staple may be separated from its batch and used for the desired stapling operation.

In order to support and guide the pusher 18, a support and guide rod 19 is disposed in a space 20, alongside and communicating with the magazine passage 14 for the staples. The space 20 does not extend the full length of the magazine passage 14, but stops short against a wall 21, which is to serve as a bracing wall, or end wall, against which the forward end of the guide rod 19 may rest when the stapler is assembled.

The feed slot or passage 16 for the plunger bar is relatively thin, and is approximately of the same thickness as the thickness of one of the staples 15 that is to be used in the device. The staples, when inserted in the magazine passage 14, are adapted to be moved forward towards the feed slot 16 by the feeder or pusher device 18, which is placed in position in the magazine passage 14 after the staples have been inserted.

The feed mechanism includes, in addition to the pusher 23, the supporting and guide rod 19 and a biasing spring 25 that is supported on the rod and anchored, or braced, at its back end to react against, and to push, the feeder or pusher 18 forward against the staples. The pusher 18 has a cross-section similar to that of the staples, and, in addition, is provided with two laterally extending lugs 26 and 27 that serve as bearing and guide pieces. These bearing lugs 26 and 27 may be pressed up from the body of the pusher 18 in its formation as a complete stamping, or the bearing pieces may be otherwise formed as a U-shaped element to be inserted through two correspondingly spaced slots in the pusher 18. The longitudinal magazine passage 14 in the top shell 11 is of substantially inverted-U shape with a sufficient enlargement above the body of the U to provide space for the support and guide rod 19 and for the bearing pieces or lugs 26 and 27 of the pusher 18.

As already explained, the forward end of the guide rod 19 is arranged to rest against the inner wall surface 21. The other end of the guide rod 19 is disposed in a recess concentrically and coaxially located in the bottom shell 12.

When the guide rod 19 is co-axially disposed, as in Figure 1, the staples must necessarily be disposed off center. That in itself is not objectionable since it is desirable to dispose the staples as near as possible to the exit plane where the staples leave the feed slot 16 to engage the papers that are to be stapled, so that the staple will have as little movement as possible. However, since the lugs 26 and 27 of the pusher 18 are located with their openings concentric with the stapler, the short length of each lug between its opening and the back surface of the pusher 18 contributes unnecessarily to a radial enlargement of the tubular shell 11, merely because space must be allowed to accommodate those lugs 26 and 27. That equivalent space is therefore also wasted in the body of the top shell opposite to the space occupied by the staples.

A further object of my invention, therefore, is to provide a design in which the diameter of the

device may be made smaller than required with a concentric guide rod, such as is employed in Figure 1.

In order to accomplish this, I have arranged to locate the staples as close to center as possible, and, in Figure 2, I illustrate them actually crossing the center line or axis of the device. Since the two shells are to be threaded together, however, it is necessary not only that the shells be concentric, but that the guide rod 19 shall permit concentric rotation of the two shells for separation, or for re-closure after inserting a unit batch of staples in the magazine passage.

In order to achieve all of these essential features and operations to permit a reduced diameter of the shells, I bend the feed rod as at point 30, so the pivotally anchored end 31 of the rod will be concentrically disposed, to serve as a journal about which the bottom shell 12 may be rotated as it is joined to, and separated from, the top shell 11. At the same time the eccentric body portion of the guide and feed rod 19 has sufficient space within concentric chamber 32, in the bottom shell 12 to permit that bottom shell to rotate freely without affecting, or being affected by, the guide rod or spring.

In Figure 7 I have illustrated the pivotal end of the guide rod resting in a concentric recess 33 in a transverse wall 34 of the lower tubular shell 12. In order to simplify and expedite the assembly of the complete unit, the pivotal end 31 is rotatably anchored in a disc or washer 35 of such size as to provide an easy sliding fit in the concentric hole 32 in the shell 12. The disc or washer 35 may be fixed against casual removal from the pivotal end of the rod by slightly enlarging the end 36 of the rod, and pinching one or more lugs 37 on the rod on the inner side of the positioning disc or washer 35.

The front end of the device, which is the lower or outer end of the bottom shell 12, is shaped to receive a mechanical pencil unit which is, in itself, no part of my invention, and which is shown merely to illustrate the type of device to which the hand operable stapler embodying my invention, is applied, so the entire unit may provide a desirable and useful tool for engineers and mechanics who have frequent occasion to fasten certain papers together as they have marked them. Although I have shown my invention as applied to a pencil element, it should be clear that it might just as well be applied to a pen, with some slight modification merely in the relative dimensions.

By means of the arrangement shown in Figure 1 and in Figure 2, whereby the front or top end of the guide rod presses against the surface of the wall 21 in the upper shell 11 after the two shells 11 and 12 have been substantially threaded together, sufficient friction will be provided between the threaded portions, and the re-action pressure asserted upon them by the guide rod 19, to provide a tight joint.

On the other hand, the threaded portions themselves may be arranged to provide a tight joint independently of any reaction pressure from the guide rod 19. In either case, the threaded ring portion at the lower end of the top shell 11 may be made thicker or suitably reinforced.

As shown in Figures 1, 2 and 6, the front portion of the batch of staples will be held between the platform surface 40 upon which the staples rest, and the shoulder portions 41 and 42 of the wall 21 adjacent the end of the magazine pas-

sage 14. The passage 14 is of such dimension as to permit a relatively easy slide movement of the staples without too much looseness.

When the batch of staples is moved forward by the pusher 18, the front, or leading, staple will engage the plunger or staple driver 17 if that driver is in its depressed position. When that staple driver is raised to its upper terminal position, it will move out of the way of the staples, and the entire batch will be moved forward to place the leading staple in the feed slot, where it will be directly below, and in the path of movement of, the staple driver 17. Thereupon, when the staple driver 17 is pressed downward by its thumb piece or head 17a, the driver will shear the leading staple from its batch, and force it downwardly and out of the feed slot 16, to perforate any papers 44 that may be placed in the path of the staple between the lower end of the feed slot 16 and an anvil 45.

The anvil 45 consists of a metal element having one end 46 anchored to the body of the shell 11 by a suitable means such as two anchoring screws 47; and a forward portion 48 bent out of the plane of the anchored portion 46 to be slightly spaced from the end of the slot 16 to provide a space 49 into which papers may be inserted that are to be fastened by the staple.

When the staple is pressed down through the feed slot through the papers, by the staple driver or plunger 17, the lower ends of the staple engage curved slots in the anvil 45 and are turned upwardly, and closed, as shown in Figure 4.

When the driver 17 is in its lowermost position towards the anvil 45, the head or thumb piece 17a is arranged to be flush with the longitudinal periphery. To provide space to receive that thumb piece 17a, the shell 12 is provided with an arcuate recess 51 extending partially around the periphery of the shell as shown in Figures 1 and 2.

In order to permit the driver to be easily withdrawn to its raised position, the thumb piece 17a is corrugated or knurled on its side edge surfaces.

In order to prevent the driver 17 from being entirely withdrawn from its slot, an anchoring pin 52 is disposed in the top portion of the shell beyond the forward slot 16, with the inner end of the pin 52 extending into a longitudinal slot 53 in the driver 17.

The outer end of the shell 11 beyond the anchoring pin is shaped to constitute an annular ring portion 54 to receive an eraser 55.

A cap 56 fits over the annular ring 54 to enclose the eraser when it is not to be used.

A clip 60' is fastened on the top shell 11 by one of the anchoring screws 47 as shown in Figures 1 and 2.

My invention is thus directed to a hand operable stapler of simplified construction and design which may be made up of molded materials to provide a light, strong and inexpensive hand operable device that may be conveniently carried as part of a conventional pencil or pen.

In the construction shown in Figures 1 and 2, I have illustrated the shells as being formed of a molded or plastic material.

As a modification of these structures, I have illustrated in Figures 4 to 17, a construction wherein a metal magazine 60 is provided to receive the batch of staples, and to guide them to the feed slot.

Two cooperating channel sections 61 and 62

are arranged to be assembled on end with the magazine section 60 to provide the complete guiding positions for the staples and the pressure bar.

5 The assembled metallic elements 60, 61 and 62 are then made to constitute the inserts in the finished molded shells. With this arrangement the metal elements provide the guide surfaces for the plunger and the staples, instead of the molded material itself providing the guiding surfaces as in the construction surfaces shown in Figures 1 and 2.

In order to hold the metal parts while the molded material is formed around them, the elements 60, 61 and 62 are provided with suitably located lugs 63 pressed out from the body of the metal parts to fit over corresponding portions of the adjacent co-fitting parts.

In Fig. 18, of the second modification, is shown 20 a section similar to Fig. 6 but with the metal guide 60 of Fig. 14 as a molded insert in the front magazine body 11. Otherwise the other parts are the same as in the first form, shown in Fig.

1. The guide rod 19 for the staple pusher extends through the arch 64, along the top wall of metal staple guide 60, and seats against the face wall 61a of the channel 61, similarly to the manner in which the corresponding guide rod rests against wall 21 in Fig. 1.

25 In order to permit the operator of the stapling device to raise the staple driver 17 with the same thumb, immediately after pressing the bar downward, I provide a lifting lever 65 that is pivotally supported on a pin 66 which is anchored in the body of the shell. The forward arm 66 of the lever 65 projects under the head piece 17a of the staple driver, and the other arm 67 is so constructed as to extend slightly above the contour of the shell; when the pressure bar is pressed 30 downward to its limit position. Thus, when the thumb of the operator presses on the arm 67, the lever will be rotated slightly to lift the pressure bar upward out of its groove. It may then be easily raised, if necessary, a sufficiently further distance to move to its upper limit position. The pivot pin 66 may be easily positioned in a suitably drilled hole after the shell has been formed.

In Figure 11 I have shown the manner in which 35 the anvil of the modification of Figure 2 is seated in a recess to provide additional holding pressure against the sides of the anvil, so it will be held more tightly by the anchoring screws, as is shown in Figure 6. The outer contour of the anvil of the modification of Figure 2 and Figure 11 is 40 preferably curved to correspond to the circular contour of the shell.

Although I have referred to the shells as being 45 made of plastic material, it will be understood that they may be made of such molded material of any kind of plastic, or they may be made of metal die castings.

50 My invention is not limited to any of the specific details of construction that are shown, since they may be variously modified without departing from the spirit and scope of my invention as set forth in the appended claims.

I claim as my invention:

55 1. A stapler to be held and used in one hand, consisting of a tubular magazine having a longitudinal passage to receive a unit batch of separable staples; a narrow feed slot to receive and guide a single staple; a thin reciprocable staple driver slidably in said feed slot, from one upper terminal position to a lower pressing position to separate, move and compress a staple; an en-

larged head at the top of the staple driver to permit easy raising of the plate and to provide a pressure surface on its top to receive the thumb of the hand as an operating force, said head, when depressed, fitting into a recess in the tubular member; an anvil anchored on the side of the magazine and in the path of the staple driver to cooperate with the staple driver to compress a staple; and a spring biased pusher behind the staples and biasing them towards the feed slot into the path of the staple driver.

2. A hand stapler to be held in one hand and to be operated by the thumb, comprising a front tubular member having a metal guide member therein to serve as a magazine for staples; that guide member having an internal longitudinal magazine passage to receive and to guide the staples, the back end of the passage being open to permit the staples to be inserted into the longitudinal passage; the front end of the means in the tubular member being closed to provide a narrow feed slot to receive a single staple at the forward end of the longitudinal passage; a staple driver fitting into the slot between the end of the member and the front end of the magazine passage, and movable from a top limit position to a lower limit position to compress a staple received in the feed slot; an anvil plate below the lower end of the feed slot to serve as a reaction plate against which the pressure plate may compress the staples; a rear tubular member to close the back end of the front tubular member; a pusher to fit into the magazine passage to push the staples toward the feed slot at the front end of the magazine; a support and guide rod for the pusher; a biasing spring on the rod to bias the pusher forward; and means on the rear tubular member to support one end of the rod; the two tubular members being separable to permit insertion of a batch of staples.

3. A hand stapler to be operable by a thumb while held in one hand, comprising a front and a rear tubular element, both being threaded to be connectable in axial alignment; the front tubular element having its threaded end open and communicating with a longitudinal passage to receive a group unit of separable staples; a pusher to fit into the passage behind the staples; a supporting and guiding rod for the pusher; a compressable helical spring on the guide rod and braced against a portion of the guide rod to assert a biasing force against the pusher in a direction to move the staples towards the front end of the front tubular element; a receiving slot

for the front staple on the group unit; and a reciprocable staple driver in the slot to separate the front staple from its group and to force it through a selected predetermined path; an anvil anchored on the side of the front tubular element in the path of the staple driver to provide a reaction surface against which the staple driver may compress the staple after forcing it through the papers that are to be fastened together; and means within the rear tubular element to support one end of the guide rod for the pusher.

4. A hand operable stapler to be held in one hand and operated by the thumb, comprising a tubular magazine body having a metal guide member therein shaped to have a longitudinal passage serving to receive and guide a batch of staples to a transverse slot, said slot being of width and thickness to receive the leading staple of a batch in the longitudinal passage; means adapted to be disposed behind the staples to bias them toward the transverse slot; a staple driver having a thumb plate and being reciprocable in the transverse slot to admit the leading staple into the slot and to separate that staple from its batch and force it through papers to be secured; and an anvil in the path of the staple driver to cooperate with the bar to compress and clinch the staple, and a removable tubular closure separable from the magazine body to permit the insertion of a batch of staples.

5. A stapler as in claim 4, in which a lifting lever is pivotally disposed with one end under the thumb plate of the staple driver and the other end in position at the periphery of the magazine body and adapted to be depressed by the thumb to raise the staple driver after a clinching operation.

6. A stapler to be held in one hand and to be operated by the thumb, comprising a tubular body having a longitudinal magazine passage and a communicating transverse slot; a staple driver reciprocable in the slot and having a thumb plate at its top to enable thumb pressure to depress the staple driver, the thumb plate being substantially arcuate on its outer contour; and the tubular body having a peripheral arcuate recess to receive the thumb plate.

7. A stapler as in claim 6, in which a thumb-operable lever is mounted on the tubular body to be operated by the thumb to lift the staple driver from a depressed position to an elevated position.

WILLIAM D. FALTZ.
